UNITED STATES PATENT OFFICE.

ALEXANDER MALM, OF NEW YORK, ASSIGNOR TO THEODORE W. SHERIDAN, OF BROOKLYN, NEW YORK, AND CHARLES B. SHERIDAN, OF ORANGE, NEW JERSEY.

PAPER-CUTTER.

SPECIFICATION forming part of Letters Patent No. 446,359, dated February 10, 1891.

Application filed October 23, 1890. Serial No. 369,099. (No model.)

To all whom it may concern:

Be it known that I, ALEXANDER MALM, a citizen of the United States, residing at New York, in the county and State of New York, have invented new and useful Improvements 5 in Paper-Cutters, of which the following is a specification.

This invention relates to improvements in paper-cutters; and the invention consists in 10 the details of construction set forth in the following specification and claims, and illustrated in the annexed drawings, in which—

Figure 1 is a face elevation of a paper-cutter containing my invention. Fig. 2 is a plan 15 view of Fig. 1. Fig. 3 is a section along x x , Fig. 1. Fig. 4 is a detail view sectioned along y y , Fig. 3. Fig. 5 is a section along z z , Fig. 2. Fig. 6 is a diagram hereinafter explained.

20 In the drawings, the letter A indicates a support or frame having a table B for the paper C, as also a clamping-bar D and a cutter or blade E to clamp and cut the paper. F is the cutter-head. The construction and 25 operation of these parts are well known and need no detailed description.

The driving-shaft G has the usual fast and loose pulleys H H and a fly-wheel I. Said shaft G gives motion to the driving-pinion 30 K, gearing into the gear-wheel M on shaft O. At either end of shaft O an eccentric d, Figs. 3 and 4, is fixed to frame A. About each eccentric sits a strap e, from which extends a wrist pin or connection f. A connecting 35 piece or slide g joins each of the pins or connections f to the wrist-pins P, from which extend links Q to the cutter-head F. The gear M is located at one end of the shaft O, and one of the spokes of the gear M has a 40 slot or guideway h for one of the slides g, so as to form a carrier for the said slide. The other connecting piece or slide is guided in a similar guideway h, formed in a carrier or disk i, secured to the other end of shaft O.

45 When the shaft O revolves in the direction of the arrow, Fig. 3, the pins or connections f are carried about the eccentrics d, and in its descent each connection f is made to pass close to the shaft O. As the circumferential speed diminishes the more closely the shaft O is approached, and as such close approach to the shaft furnishes great lever 50

power, the descent of the connection f and of the cutter-head F is slow, and said cutter-head is enabled to exert considerable force 55 so as to carry its knife D through the material. In its ascent each of the pins f travels along that part of its eccentric d which lies farther from the shaft O, and the consequent increase in circumferential speed causes the 60 connections f and cutter-head F to rise or return rapidly to the starting-point. The guides h allow the connections f sufficient play to approach and recede from shaft O.

The movement of one of the pins f is illustrated by the diagram, Fig. 6, in which O indicates the driving-shaft, d the stationary eccentric, and f the pin which imparts motion to the cutter-head F. As the pin f moves from the highest position (shown in full lines) 70 to the lowest position (shown in dotted lines) the shaft O turns seven-twelfths ($\frac{7}{12}$) of one revolution, and the return movement of the pin f from its lowest to its highest position is completed while the shaft O turns five-twelfths ($\frac{5}{12}$) of one revolution; or, in other words, the downward stroke of the cutter-head 75 will be completed in seven seconds and the upward stroke in five seconds if the shaft O makes one revolution in twelve seconds. 80

What I claim as new, and desire to secure by Letters Patent, is—

1. In a paper-cutter, the combination, with a cutter or blade and a shaft O, of an eccentric, a pin or connection f, carried by the shaft about the eccentric, and a pitman connecting the pin and cutter, substantially as described.

2. In a paper-cutter, the combination, with a cutter, a shaft, an eccentric, and a pin or connection f, carried by the shaft about the eccentric, of a pitman for connecting the pin and cutter, and a carrier or disk for connecting the pin and the shaft O, said carrier having a suitable guideway h for the pin or connection, substantially as described. 95

In testimony whereof I have hereunto set my hand in the presence of two subscribing witnesses.

ALEXANDER MALM.
